US0D1019880S

(12) **United States Design Patent** (10) **Patent No.:** **US D1,019,880 S**
(45) **Date of Patent:** **** Mar. 26, 2024**

(54) **WATER TREATMENT SYSTEM**

(71) Applicant: **Access Business Group International LLC**, Ada, MI (US)

(72) Inventors: **Daniel L. Schlenk**, Grand Rapids, MI (US); **Rebecca C. Musante**, Wyoming, MI (US); **Tedmund A. Robbins**, Hastings, MI (US); **Cynthia Andreason**, Grand Rapids, MI (US); **Matthew J. Norconk**, Grand Rapids, MI (US); **Timothy D. Stoepker**, Grand Rapids, MI (US); **Sarah E. Gesink**, Caledonia, MI (US)

(73) Assignee: **Access Business Group International LLC**, Ada, MI (US)

(**) Term: **15 Years**

(21) Appl. No.: **29/832,594**

(22) Filed: **Mar. 29, 2022**

(51) LOC (14) Cl. **23-01**

(52) U.S. Cl.

USPC **D23/206**

(58) **Field of Classification Search**

USPC D23/207, 208, 209, 210; D24/162

(57) **CLAIM**

The ornamental design for a water treatment system, as shown and described.

DESCRIPTION

FIG. 1 is a top, right, front perspective view of the water treatment system;

FIG. 2 is a top, left, front perspective view thereof;

FIG. 3 is a top, right, rear perspective view thereof;

FIG. 4 is a top, left, rear perspective view thereof;

FIG. 5 is a bottom, right, front perspective view thereof;

FIG. 6 is a bottom, right, rear perspective view thereof;

FIG. 7 is a front view thereof;

FIG. 8 is a back view thereof;

FIG. 9 is a top view thereof;

FIG. 10 is a bottom view thereof;

FIG. 11 is a left side view thereof; and,

FIG. 12 is a right side view thereof.

1 Claim, 10 Drawing Sheets
